UNITED STATES PATENT OFFICE.

CHARLES D. DE FOREST, OF PITTSBURG, PENNSYLVANIA, ASSIGNOR, BY DIRECT AND MESNE ASSIGNMENTS, OF FIVE-EIGHTHS TO JOHN T. KENNA, OF SAME PLACE, AND JOHN H. RONEY, OF ALLEGHENY, PENNSYLVANIA.

COLLAR-AND-SOCKET MACHINE.

SPECIFICATION forming part of Letters Patent No. 608,584, dated August 9, 1898.

Application filed June 5, 1895. Renewed October 23, 1897. Serial No. 656,193. (No model.)

To all whom it may concern:

Be it known that I, CHARLES D. DE FOREST, a citizen of the United States, residing at Pittsburgh, in the county of Allegheny and State of Pennsylvania, have invented certain new and useful Improvements in Collar - and - Socket Machines; and I do hereby declare the following to be a full, clear, and exact description of the invention, such as will enable others skilled in the art to which it pertains to make and use the same, reference being had to the accompanying drawings, which form a part of this specification.

This invention relates to certain new and useful improvements in machines for making sleeves for pipes and the like.

The object of the invention is to construct a machine of the above-referred-to class that will be strong, durable, and effectual in its operation.

The invention has for its further object the provision of novel means whereby the mechanism may be easily and readily adjusted to manufacture different sizes of sleeves.

The invention consists in the novel construction, combination, and arrangement of parts to be hereinafter more particularly described, and specifically pointed out in the claims.

In describing the invention in detail reference is had to the accompanying drawings, forming a part of this specification and wherein like figures of reference indicate similar parts throughout the several views, in which—

Figure 1 is a front elevation of my improved machine for making sleeves. Fig. 2 is a side elevation of the movable bearing. Fig. 3 is a front view of the same. Fig. 4 is a vertical sectional view. Fig. 5 is a detail side view of the connection between the piston and horizontal shaft. Fig. 6 is a plan view of the same. Fig. 7 is a modification of the arrangement of the rolls. Fig. 8 is a detail view of the levers and valves.

In the drawings, 1 indicates the pulley communicating power to the pulley 2 by means of a belt 3, rotating a horizontal shaft 4, carrying on its end a plunger 5. Said shaft is mounted in bearings 6, 7, and 8 and carries a fly-wheel 9.

The reference - figure 10 represents the

steam-cylinder, provided with an ordinary piston-head and piston 11, coupled at 12 to a coupling 13, attached to the horizontal shaft 14, the former being mounted in a stationary bearing 15 and the latter in a movable bearing 16, operating in guides 17. At the end of the horizontal shaft is provided with a shaper 18. The motion of the piston-rod is reversed by means of a series of levers 19 19, opening and closing the outlet-valves 20 and 21, the inlet-valve being indicated by the reference-figure 22, and 22^a indicates the reversing-valve. The upright standards 23 23 serve as bearings for the shaft 24, carrying the roll 24^a, the latter being adjustable vertically by means of lever-pawl 25 25 and a connecting-rod 26 of the miter-gear or ratchet wheels 27, carrying vertical screw-threaded shafts 28 28, operating the bearing-blocks of the shaft 24. By this means the roll 24^a may be raised and lowered.

The operation of the machine is as follows: The hot metal is placed between the shaper and plunger and the valve set so as to drive the piston-rod carrying the shaper toward the plunger, and the machine is set into operation and forms the sleeve or socket. Any-sized shaper and plunger may be substituted and the roll set accordingly.

It will be seen that the general characteristics of the mechanism consist in having a supporting or forming roll 18, which is adapted to support the entire body of the welding metal and is adapted to be moved longitudinally without stopping the machine and to carry the welded metal bodily with it as it moves longitudinally; secondly, in having a pressing or welding roll opposite to the normally-operative position of the shaping or forming roll, and, thirdly, in having a stripping part which shall discharge the metal from the shaping and forming roll as the latter is moving longitudinally.

There can be numerous modifications of the parts to attain the ends of those referred to. In the present construction one of the flanges on the pressing or welding roll serves as a stripper, the metal being fitted and pressed into the groove or cavity in the periphery of said roll, so that the flange prevents the movement of the latter with the other roll.

The forming or shaping roll 18 (in that it supports the entire body of the welded metal) differs from those heretofore suggested for this purpose, which were made in two disk-like 5 halves which were separable in the midway vertical plane for the purpose of holding a narrow ring welded thereon to drop immediately downward when the two halves were separated. The present mechanism is for the 10 treating of relatively long sections of tubing, thimbles, couplings, &c., and hence a firm support is requisite at the central part of the metal longitudinally, and to attain this a support continues through the thimble or coupling, and this requires the presence of a stripper which can remove the metal from the forming-roll as it is being moved bodily longitudinally with said roll. When the two 15 parts of the forming or shaping device are separable at the midway plane of the pressing or welding roll, a bead or fin is apt to be formed on the metal at the middle of its inner surface, which requires subsequent turning or machine-work to permit its use as a 20 coupler-pin tubing, and this is avoided by having the supporting-surface continuous and providing a stripper for removing the metal from the roll.

It will be seen that various changes may be 25 made in the details of construction of my device without departing from the general spirit of the same.

Having fully described my invention, what I claim as new, and desire to secure by Letters 30 Patent, is—

1. In a machine for making sleeves for pipes, the combination of the steam-cylinder and its piston, the endwise-movable shaft coupled to said piston and provided with a shaper, 35 the reversing valve mechanism arranged in connection with said steam-cylinder and adapted to provide for the reversing of the movement of said shaft, with its shaper, the rotatable plunger opposed to said shaper and the finishing-roll arranged contiguously to 40 and above said longitudinally-movable shaper and rotatable plunger, substantially as set forth.

2. In a machine for making sleeves for 45 pipes, the combination of the cylinder and its piston, the endwise-movable shaft provided with a shaper and coupled to said piston, the reversing valve mechanism comprising a series of valves arranged in pipes connecting 50 with the ends of said cylinder and in a pipe connecting with the aforesaid pipes and interacting levers between said valves, a rotary plunger opposed to said shaper, and a finishing-roll arranged contiguously to said shaper 55 and plunger, substantially as specified.

3. In a machine for making sleeves for 60 pipes, the combination of the cylinder and its piston, the endwise-movable shaft coupled to said piston and provided with a shaper, the reversing mechanism for said piston and shaft with its shaper, a rotary plunger opposed to 65 said shaper, the finishing-roll arranged in

juxtaposition with said shaper and plunger, and the mechanism for effecting the vertical adjustment of said finishing-roll comprising 70 the vertical screw-threaded shafts engaging the bearings of the shaft carrying said finishing-roll, and provided with the miter or ratchet wheels and the connected lever-paws adapted to engage said ratchet-wheels, substantially as described.

4. In a device of the character described, a series of two or more rotatable rolls, means for rotating one or more of them, means for imparting to one of said rolls a longitudinal 80 movement independently of the rotation-causing devices, and a stripper, substantially as set forth.

5. In a device of the character described, a series of two or more rotatable rolls, means 85 for rotating one or more thereof, means for imparting to one of said rolls a longitudinal movement independently of the rotation-causing devices, and a stripper extending around and concentric with one of the rolls, for discharging the welded metal, substantially as forth.

6. In a mechanism of the character described, the combination of a pressing or welding roll, a holding or forming roll, a rotary 95 abutment contacting with the holding or forming roll to relieve it of thrust, and means for imparting longitudinal motion to the holding or forming roll, substantially as set forth.

7. In a mechanism of the character described, the combination of a pressing or welding roll having a groove or flanges, and a holding or forming roll having one or more flanges, and means for moving the holding or forming roll longitudinally, one of the aforesaid 105 flanges around the rolls being adapted to serve as a stripper, substantially as set forth.

8. In a mechanism of the character described, the combination of a longitudinal movable holding or forming roll having radially-extending flanges and a metal-supporting surface extending continuously from one flange to the other, whereby said roll is adapted to carry the welded metal bodily when it moves longitudinally, an opposing pressing 110 or welding roll, and a stripper for removing the welded metal from the carrying-surface on the longitudinally-moving roll, substantially as set forth.

9. In a machine of the class described, the 115 combination of a welding-roll, a supporting-roll arranged below the welding-roll, and having a continuous supporting-surface extending from one side of the welding-roll to the opposite side thereof, and means for moving 120 longitudinally the last said roll for positively forcing the welded metal therefrom, substantially as set forth.

10. In a machine of the character described, the combination of a metal-supporting roll 125 comprising two sections, each provided with an annular flange or abutment, and one adapted to have its body portion completely surrounded by the body portion of the other sec-

tion, a welding-roll arranged above said supporting-roll, means for moving the outer section of said supporting-roll longitudinally of its axis, and means for preventing the metal

5 moving with said adjustable section of the supporting-roll, substantially as set forth.

11. In a machine of the character described, the combination of a metal-supporting roll having an annular flange or abutment around 10 each end, a welding-roll mounted above said supporting-roll, means for rotating one or more of said rolls, means for moving one of

the flanges around the supporting-roll longitudinally of the axis thereof, and means for positively forcing the metal from said supporting-roll, substantially as set forth. 15

In testimony that I claim the foregoing I hereunto affix my signature this 27th day of December, A. D. 1894.

CHARLES D. DE FOREST. [L. S.]
